The ornamental design for an antenna stand, as shown and described.

DESCRIPTION

FIG. 1 is a front top perspective view of an antenna stand showing our new design;

FIG. 2 is a rear bottom perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof; and,

FIG. 8 is a rear elevational view thereof.

In the drawings, the broken lines depict environmental subject matter only and form no part of the claimed design.
